(57) **CLAIM**

We claim the ornamental design for a machine for cutting a window covering, as shown and described.

DESCRIPTION

FIG. 1 is a perspective view showing our new design for a machine for cutting a window covering;

FIG. 2 is a front view showing our new design shown in FIG. 1;

FIG. 3 is a back view showing our new design shown in FIG. 1;

FIG. 4 is a top view showing our new design shown in FIG. 1; FIG. 5 is a bottom view showing our new design shown in FIG. 1;

FIG. 6 is a left side view showing our new design shown in FIG. 1; and,

FIG. 7 is a right side view showing our new design shown in FIG. 1.

The portions shown in dashed lines in FIG. 4 represent a light pattern visible through a transparent top of the machine.

The portions shown in broken lines are not part of the claimed design but show the environment in which the design is associated.
